UNITED STATES PATENT OFFICE.

CHARLES S. DIKEMAN, OF TORRINGTON, CONNECTICUT.

BICYCLE.

SPECIFICATION forming part of Letters Patent No. 640,884, dated January 9, 1900.

Application filed March 7, 1898. Serial No. 672,882. (No model.)

To all whom it may concern:

Be it known that I, CHARLES S. DIKEMAN, of Torrington, in the county of Litchfield and State of Connecticut, have invented certain new and useful Improvements in Bicycles; and I do hereby declare the following to be a full, clear, and exact description of the invention, such as will enable others skilled in the art to which it appertains to make and use the same.

My invention relates to an improvement in bicycles, and more particularly it pertains to the hangers and bearings for pedal-cranks, the object being to provide means for removably securing the crank-hanger to the bicycle-frame; and it consists, essentially, in a hanger or barrel removably held in the frame connection by screws, bolts, or otherwise and in certain additional details of construction and combinations of parts, which will be hereinafter described, and pointed out in the claims.

In the accompanying drawings, Figure 1 is a view in side elevation of the frame. Fig. 2 is a view in front elevation of a portion of the frame, with the pedal-shaft in position therein. Fig. 3 is a vertical transverse section through the bearing. Figs. 4 and 5 are detail views of the frame connection, and Figs. 6 and 7 are detail views of the detachable hanger or barrel.

A represents the frame of the machine. This comprises the usual tubing, arranged in the usual diamond shape. B is a connection for holding the several tubes of the frame together at the pedal-crank. The connection comprises the rounded portion 1, which constitutes a socket, and the several thimbles 2, corresponding in number to the several tubes of the frame centering at that point and constructed and adapted to be inserted into the ends of said tubes and shrunk, brazed, or otherwise secured rigidly therein, whereby to form a secure and permanent union at this point.

C indicates the hanger. It is composed of a barrel 5 and the shank 6. The latter is inserted in the open lower end of the tube 7 of the frame, the barrel fitting the concavity of

the rounded or half-round portion 1 of the connection. This hanger may be removably held in place in any convenient manner—as, for instance, by the bolt or nut 9, passed through the shank 6 and lower end of tube 7, and screws 10, 10, extending through the connection into the shell of the hanger, as shown.

With such a construction as described it will be seen how readily the hanger can be removed or replaced. Also the construction is such a one as will afford all needed strength and rigidity.

Through the hanger the crank-axle is passed, it being provided with the bearing-cups 12, 12 and the ball-bearings 13, 13, as customary in all modern machines of this type. These parts might obviously be modified, as well as the other details of the invention, without departing from the spirit and scope of my invention, and hence I do not wish to be limited to the exact construction herein set forth; but,

Having fully described my invention, what I claim as new, and desire to secure by Letters Patent, is—

1. In a bicycle, the combination with a frame, of a connection for securing certain of the tubes of the frame together, said connection having an open half-round socket, and a hanger comprising a barrel and shank, the barrel fitting the socket and the shank entering one of the tubes of the frame and removably secured therein.

2. In a bicycle, the combination with a frame, and a connection comprising the rounded socket portion and thimbles secured in the contiguous ends of certain tubes forming the frame, a hanger comprising a barrel and shank adapted to enter the socket portion and one of the tubes respectively and means for holding the hanger removably in place.

In testimony whereof I have signed this specification in the presence of two subscribing witnesses.

CHARLES S. DIKEMAN.
